STEERING WHEEL

Carl H. Renner, Detroit, Mich., assignor to General Motors Corporation, Detroit, Mich., a corporation of Delaware

Application February 18, 1955, Serial No. 34,568

Term of patent 7 years

(Cl. D14—30)

Fig. 1

Fig. 2

Fig. 1 is an elevational view of the steering wheel showing my new design; and

Fig. 2 is a side view of the steering wheel.

I claim:

The ornamental design for a steering wheel, substantially as shown.
